UNITED STATES PATENT OFFICE.

ABRAHAM G. LOTT, OF WASHINGTON, DISTRICT OF COLUMBIA.

GOLF-PRACTISING DEVICE.

1,191,444.

Specification of Letters Patent. Patented July 18, 1916.

Application filed April 8, 1916. Serial No. 89,840.

To all whom it may concern:

Be it known that I, ABRAHAM G. LOTT, a citizen of the United States, residing at Washington, in the District of Columbia, have invented certain new and useful Improvements in Golf-Practising Devices, of which the following is a specification.

This invention relates in general to game apparatus, and more particularly to a novel improvement in golf practising devices.

The average golfer is handicapped to a great extent by not having the time to devote to the game to obtain the necessary practice to properly develop the correct body poise and arm swing to obtain the best results in the driving stroke. As is well known, the head of the "driver" must be swung in a certain path in order to hit the ball true for a straight drive, and any deviation from this path results in driving the ball out of the desired course. Obviously, the only way to acquire this correct swing and body posture is by practice.

Accordingly, the present invention has in view, as a general object, a device whereby the correct body position and arm movements of the golfer may be practised indoors at home, thereby not only providing a beneficial and enjoyable exercise, but at the same time developing the correct swing of the golf club necessary to perfect the driving stroke.

A further and more specific object of the invention is to provide a device whereby it is possible to take repeated strokes while standing in one position, and without any adjustment of the device. In this connection, the invention also proposes to provide a fixed objective or target which will aid in training the eye to remain fixed during the entire execution of the stroke, and at the same time readily enable the golfer to distinguish a good stroke from a poor one.

Various types of golf practising devices have been proposed, but on account of their complex construction and expensive nature their general use has been more or less prohibited. Therefore, the present invention has in view a device that is not only simple and inexpensive, but strong and durable, and susceptible of a neat and attractive commercial embodiment which can be used indoors or outside without alteration of the floor or ground. Thus, it will be apparent that the invention is particularly adapted to be placed in the golfer's room or at the club

house and used morning or evening, or before starting out to play a game over the golf course.

With the above and other objects in view which will more readily appear as the nature of the invention is better understood, the same consists in the novel construction, combination and arrangement of parts hereinafter more fully described, illustrated and claimed.

A preferred and practical embodiment of the invention is illustrated in the accompanying drawings, in which—

Figure 1 is a perspective view of the invention showing the head of a golf club and its relation to the target or objective member just prior to striking, the path of the club during the stroke being indicated by the arrows. Fig. 2 is a longitudinal sectional view showing the device resting upon the ground or floor and engaged with suitable anchoring means. Fig. 3 is a perspective view of the device before being assembled, as shown in Fig. 1. Fig. 4 is a view similar to Fig. 1, showing the board or base member of Fig. 2 inverted to facilitate the use of a modified form of target. Fig. 5 is a perspective view of a preferred commercial form of the invention. Fig. 6 is a longitudinal sectional view of the device shown in Fig. 5. Fig. 7 is a cross-section of the construction, shown in Figs. 5 and 6. Fig. 8 is a perspective view of the target holding clips used in the form of the preferred form of the invention shown in Figs. 5, 6, and 7.

Similar reference characters designate corresponding parts throughout the several figures of the drawings.

In carrying out the invention it is proposed to employ a suitable base member 1, which as shown in the drawings, is preferably of oblong form, and of suitable size and dimensions to constitute an effective background and playing board. It is preferred to make this base member 1 of wood, and provide the same with the flat playing surfaces 2, which may be painted or colored green to more closely simulate the color of the golf course.

Any suitable means may be utilized for temporarily or permanently securing the base member to a floor or on the ground, but an example of a simple and effective way of accomplishing this result is shown in the drawings and consists in providing the base

member with the anchor openings 3 for receiving a suitable anchor stud 4 to prevent the escapement or turning of the board under the heavy blow usually imparted to the 5 objective or target member 5 carried thereby, and representing a golf ball. This stud 4 may be of any desired character or type, and when the device is used indoors is preferably rigidly embedded in the floor F, as 10 shown in Fig. 2, or if the device is used out of doors on soft ground, any suitable anchoring member may be employed, which will not project above the playing surface. 15 The objective or target member 5 representing the golf ball, is held in a socket. This socket may be formed by a notch, slot or opening 6, the ends of which are preferably inclined or beveled as shown in Figs. 2 and 3, and said opening 6 also communicates 20 with a pin receiving passage 7 adapted to receive a removable pin 8 for detachably locking or holding the target to the base member. The said target or objective member 5, in the form of the invention shown 25 in Figs. 1, 2 and 3, is preferably a circular flat rubber ring, or a flexible and resilient loop or ring-like member of equivalent material which will give or yield under the blow of the head of the golf club, as shown 30 by the dotted lines in Fig. 2, and will also cause the target to automatically resume its original form and position after being struck. Or, as shown in Fig. 4, this member may be in the form of an adjustable loop 35 made from a flat piece of relatively stout elastic 9, which is detachably secured to the playing surface of the board, as indicated at 10, and held in place by means of a staple or guide device 11 as shown. The portion of 40 the elastic strip between the target loop and the pin 10, being in contrast to the playing surface, will act somewhat as a guide for the eye in determining a straight course in which to swing the golf club. 45 The foregoing description points out the distinctive and characteristic features of the invention, and these features are preferably embodied in the practical and commercial form of construction shown in Figs. 5 to 8, 50 inclusive, of the drawings. In this construction the target is raised to approximately the same level as the playing surface, instead of having the same held down in the notch 6 as shown in Figs. 1 to 4. In this preferred 55 construction, the essential features of a playing board 1 having the fastening receiving openings 3 at each end thereof, is adhered to, while the notch or opening 6 is also present. Unlike the other forms of the invention, the present construction proposes to 60 provide the playing surface 2 with a protecting cushion or facing 12, which as shown, is preferably of ribbed or ridged rubber, the same extending for the greater part of its 65 length at one side of the opening 6, and be-

ing provided with the slotted portion 13 which provides the resilient tongues 14 which normally cover the sides of the openings 6.

The target member 5 is preferably of the same ring-like character shown in Figs. 1, 2 and 3 and though held locked to the member 1 by the removable pin 8 working in the opening 7, the same is not directly engaged thereby. That is to say, in this instance, it is proposed to provide a suitable arched holding clip 15 having a flat ring-engaging body portion 16 and the pin receiving eyes 17 at each end thereof. This clip 15 is of such character and dimensions that when in service position the flat body portion 16 thereof projects slightly above the playing surface 2, but not above the top of the cushion 12, while the pin-receiving eyes at each end thereof are in alignment with the opening 7, so that the detachable holding pin 8 may be readily pushed in the eyes of the clip to hold the same firmly to the board. In connection with the resilient fingers 14, it may be noted that the same, because of their inherent resiliency will have a tendency to assist in maintaining the target ring 5 in its proper normal position. Thus, after each blow the target member will assume a position where it will be ready for the next succeeding blow or stroke.

From the foregoing, it will be apparent that the invention essentially has in view a golf playing device including a base member or carrier for a detachable and yieldable target member having a relatively fixed location on the base or carrier, whereby the operator will be able to take repeated strokes at the target without adjusting the same or altering his body position, thus, not only training the arms and body to put the necessary force and strength into the stroke, but at the same time assisting him in maintaining his eye in a fixed position which is necessary to complete the "carry through" so essential to a straight drive of a golf ball. Furthermore, the invention provides a device including a target which is so designed as to indicate the direction of the stroke, and which closely represents a golf ball, not only in appearance, but also in resistance qualities, whereby the operator will be aided in determining by the character of the blow whether or not his stroke is good or bad.

Without further description, it is thought that the many features and advantages of the invention will be readily apparent, and it will, of course, be understood that various changes in the form, proportion, and minor details of construction may be resorted to without departing from the spirit of the invention or scope of the appended claims.

I claim:

1. A golf practising device comprising a base member and a target consisting of an

upstanding self-sustaining element of flexible material held to a fixed location on the base member.

2. A golf practising device comprising a base member, a target consisting of a single element of flexible material, and a fastener for holding said element in a fixed location and in an upstanding position on the base member.

10 3. A golf practising device comprising, in combination, a holding element, a flat base member adapted to rest on the ground or floor and engageable with said holding element, and a flexible target element fitted to 15 and projecting above the base member.

4. A golf practising device comprising a base member and an elastic loop, constituting a target member held to a relatively fixed location on the base member.

20 5. A golf practising device comprising a base member and an elastic hollow loop, constituting a target member held to a relatively fixed location on the base member.

6. A golf practising device comprising a base member and a yieldable ring having a relatively fixed location on said base.

7. A golf practising device comprising a base member having a socket, a yieldable target member, and means for holding said 30 yieldable target member to the base at the socket comprising a clip member, and means for holding said clip member in the socket.

8. A golf practising device comprising a base member having a socket, a yieldable 35 target ring, an arched clip member for holding said ring to the base and fitting into

said socket, and a removable pin for engaging said base member and clip.

9. A golf practising device comprising a base member having a notch, a yieldable target ring, an arched clip member having terminal eyes adapted to engage said yieldable ring, and a detachable pin for entering the hole in said base member and engaging the eyes of the clip member.

10. A golf practising device comprising a base member, a yieldable target held to a fixed location on the base member, and a protective resilient cushion facing on the base member adjacent the target.

11. A golf practising device comprising a base member, a yieldable target held to a fixed position on the base member, and a protective cushion facing on the base member and underlying the target.

12. A golf practising device comprising a base member, a yieldable target held to a fixed position on the base member, and a protective cushion facing on the base member and having a resilient portion underlying the target.

13. A golf practising device comprising a base member, a flexible target element held to a fixed location on the base member, and a resilient cushion element underlying the target element.

In testimony whereof I hereunto affix my signature in the presence of two witnesses.

ABRAHAM G. LOTT.
